GRAVURE OR LETTERPRESS CYLINDER
ENGRAVING

Theodore Hommel, Webster Groves, Mo., assignor
to Universal Match Corporation, St. Louis, Mo.,
a corporation of Delaware

Application March 18, 1950, Serial No. 150,527

5 Claims. (Cl. 95—76)

1

This invention relates in general to certain new and useful improvements in means and methods of gravure or letterpress cylinder engraving.

Gravure or letterpress cylinders are ordinarily engraved by applying a photosensitive film to the cylinder surface and exposing it to light through a so-called negative which is held tightly there-around. It is essential that the negative be held very tightly against the cylinder surface during exposure and this is usually accomplished by applying suction along the edges of the negatives to draw all the air from beneath the negative. At the present time such suction is applied by relatively complicated, expensive means and frequently the results are not wholly satisfactory.

It is, therefore, the primary object of the present invention to provide methods and means for applying suction to a negative so that the latter is securely and tightly held down against the surface of a gravure or letterpress cylinder simply and efficiently.

It is another object of the present invention to provide methods and means of the type stated which are simple, inexpensive and can be employed in a quick, time-saving manner.

It is a further object of the present invention to provide methods and means of the type stated which may be readily employed for cylinders of various lengths and diameters without necessitating extensive equipment changes and set-ups.

And with the above and other objects in view, my invention resides in the novel features of form, construction, arrangement, and combination of parts presently described and pointed out in the claims.

In the accompanying drawings (2 sheets)—

Figure 1 is a side elevational view of a cylinder step-up machine embodying the present invention;

Figure 2 is a perspective view of the edge-sealing strip forming a part of the present invention;

Figure 3 is a vertical sectional view taken along line 3—3 of Figure 1;

Figure 4 is a fragmental sectional view taken along line 4—4 of Figure 3;

Figure 5 is a transverse sectional view taken along line 5—5 of Figure 2;

Figure 6 is a transverse sectional view of a modified form of cylinder step-up machine embodying the present invention;

Figure 7 is a sectional view taken along line 7—7 of Figure 6; and

Figure 8 is a fragmentary sectional view taken along line 8—8 of Figure 7.

2

Referring now in more detail and by reference characters to the drawing, which illustrates a practical embodiment of the present invention, A designates a cylinder step-up machine of the type more fully disclosed and described in my co-pending application, Serial No. 663,178 filed on May 8, 1946, now Patent No. 2,547,527, issued April 3, 1951. The machine A comprises a base 1 having slide-ways 2 for shiftably supporting a pair of spaced parallel mandrel-holders 3, 4, through which is rotatably mounted a mandrel 5. At its one end the mandrel 5 is rotatably mounted in an intermediate bearing 6 and at its outer end in an outer bearing 7. In the space between the bearings 6, 7, the mandrel is rigidly provided with a face plate 8, having a plurality of uniformly spaced apertures 9, adapted for receiving the tongue portion 10 of a spring pressed positioning pin 11. By pulling the pin 11 outwardly to disengage the tongue portion 10 thereof, the plate may be rotated a predetermined number of degrees until the tongue portion 10 will drop back into the next aperture 9. By this means the mandrel 5 may be progressively rotated step by step through accurate fractional portions of a complete rotation.

Carried by the mandrel 5, on that portion of its length which is located between the mandrel-holders 3, 4, is a gravure cylinder C, provided upon its outer face with a photosensitive layer or film 12. Operatively mounted on the base 1, for adjustment into position adjacent to the cylinder C on opposite sides thereof, are suction bars 13 adapted to fit lengthwise over and against the longitudinal edges of a film-negative which is wrapped partially around the cylinder C, as best seen in Figure 3. The suction bars 13 are connected by conventional rubber tubes 14 to a conventional vacuum pump, the latter not being shown. Provided for co-operation with the cylinder C and the suction bars 13, is an end-sealing strip S, comprising a long flat section 16, formed of tough paper fabric or any other similar material provided upon its upper face with a marginally registering, adhesively bonded cover strip 17. Sealed between the section 16, 17, are longitudinally extending spaced parallel cord members 18, 19. The strip S is provided at uniformly spaced intervals along its inner margin 20 with a series of narrow, preferably rectangular, indentations or slots 21, all preferably of uniform size and shape. The slots 21 each cut across and, in effect, sever the cord 19 but terminate in the space between such cord 19 and cord 18, so that the latter is, in effect, unbroken throughout its length.

In use two lengths of end-sealing strip S are cut off, each being of a length approximately equaling the transverse width of the film-negative N. These two lengths are laid around the cylinder with the cover section 17 in upwardly or outwardly presented position and in such position as to partially underlie the opposite transverse margins of the film-negative N when the latter is wrapped around the cylinder C preparatory to exposure. It will be noted that the ridges formed by the cords 18, 19 will be in contact with the under face of the film-negative N, as shown in Figure 4. The ends of the strips S will extend into the suction channels 22 of the suction bars 13. It will be noted, by reference to Figure 4, that in this operative position there will be a very minute but continuous peripheral channel 23, designed by the cords 18, 19 and extending along the under face of the film-negative N. This so-called channel 23 will be in communication with the entire under face of the film-negative N through the several slots 21, so that the vacuum pump, operating through the suction bars 13 and the channels 22 thereof, will be enabled to draw the air out from between the sensitized surface 12 of the cylinder C and the under face of the film-negative N, thereby permitting the film-negative N to be forced into tight, uniform and unwrinkled contact so that a highly accurate exposure may be made.

It has been found that the sealing strip or element above described is extremely efficient and it is, at the same time, exceedingly economical and simple to use. Sealing strips constructed in accordance with the present invention may be made up in long continuous lengths upon rolls of any suitable size and may be cut off in various lengths for each particular job, depending upon the size of the particular negative which is being exposed. It has been found that where a certain size of negative is being used repeatedly the sealing strips may be used over and over.

It is also possible to provide a modified method of superimposition of the negative upon a gravure cylinder as shown in Figures 6 to 8 inclusive wherein 5' designates a mandrel substantially identical with the previously described mandrel 5. Mounted on the mandrel 5' is a gravure cylinder C' provided on its outer face with a photosensitive film 12'. Operatively mounted adjacent the mandrel 5' for co-operation therewith are hold-down bars 24 provided with longitudinally extending rubber pads 25 adapted to rest against the longitudinal edges of a film-negative N' as it lies wrapped around the cylinder C'. Also wrapped around the cylinder C' so as to underlie each of the transverse ends of the negative N' are sealing strips S, each being of such length as to terminate at its ends a substantial distance inwardly from the longitudinal margins of the film negative N'. Also applied to the cylinder C' so as to underlie, and project outwardly along, the longitudinal margins of the film negative N' are sections of tape 26 of approximately the same thickness as the sealing strips S. It should be noted that the sections of tape 26 extend across the ends of the sealing strips S and in effect form end closures across the ends of the suction channels 23 formed along the under-face of the film negative N'.

Provided for co-operation with the mandrel 5' and film negative N', are two semi-circular suction manifolds 27 connected by a suitable fitting 28 to a suction line 29. Formed preferably in-

tegrally with each manifold 27 are five radially inwardly projecting suction cups 30.

The film negative N' is punctured in five places conforming to the positions of the suction cups 30 to provide apertures 31 communicating with the suction channels 23. The suction cups 30 are then set down over the apertures 31 as shown in Figure 6 and suction applied. It has been found that a smooth, highly satisfactory superimposition of the film negative N' upon the cylinder C' can thus be obtained and the film negative N' will tend to slip down slightly over the sections of tape 26 as the suction is first applied, to adjust for slight variations in circumferential dimensions as it conforms to the cylinder C'. Once fully in place, the film negative N' will, of course, be held securely unmovingly, and without any creases or wrinkles.

It should be understood that changes and modifications in the form, construction, arrangement and combination of the several parts of the means and methods of gravure or letter-press cylinder engraving may be made and substituted for those herein shown and described without departing from the nature and principle of my invention.

Having thus described my invention, what I claim and desire to secure by Letters Patent is:

1. A photoengraving machine comprising means for supporting a photo-sensitized element, a film-negative superimposed upon said element, a tape having spaced parallel raised portions adapted for disposition under the margins of the film-negative between the under face of the film-negative and the outer face of the photosensitized element, said film-negative being provided with a plurality of small apertures opening into the space between the film-negative and said element, and means communicating with the sealed-off space between the film-negative and said element through said apertures for exhausting the air therefrom whereby to produce intimate contact between the film-negative and said elements.

2. A photoengraving machine comprising means for supporting a photo-sensitized element, a film-negative superimposed upon said element, a tape having spaced parallel raised portions adapted for disposition under the margins of the film-negative between the under face of the film-negative and the outer face of the photosensitized element, said film-negative being provided with a plurality of small apertures opening into the space between the film-negative and said element, means communicating with the sealed-off space between the film-negative and said element through said apertures for exhausting the air therefrom whereby to produce intimate contact between the film-negative and said elements, and swingable means adapted to rest against at least one margin of the film-negative and press it snugly against the photo-sensitized element.

3. A photoengraving machine comprising means for supporting a photosensitized element, a film-negative superimposed upon said element, a tape having spaced parallel raised portions adapted for disposition under the margins of the film-negative between the under face of the film-negative and the outer face of the photosensitized element, said film-negative being provided with a plurality of small apertures opening into the space between the film-negative and said element, means communicating with the sealed-off space between the film-negative and said element through said apertures for exhausting the air therefrom whereby to produce intimate contact

between the film-negative and said elements, and a swingable bar adapted to rest against a margin of the film-negative and press it snugly against the photo-sensitized element.

4. A photoengraving machine comprising a mandrel, a photo-sensitized cylinder operatively mounted on the mandrel, a flexible film-negative disposed upon and extending in overlying relation around the photosensitized cylinder, a semi-circular suction manifold operatively mounted adjacent to the mandrel in outwardly spaced concentric relation to the photosensitized cylinder, and a plurality of flexible off-takes connected to the suction manifold and extending radially inward toward the film-negative, said off-takes each terminating in a suction cup adapted to be disposed upon the outer surface of the film-negative when the latter is operatively mounted upon the cylinder.

5. A photoengraving machine comprising a mandrel, a photo-sensitized cylinder operatively mounted on the mandrel, a flexible film-negative disposed upon and extending in overlying relation around the photosensitized cylinder, a semi-circular suction manifold operatively mounted adjacent to the mandrel in outwardly spaced concentric relation to the photosensitized cylinder, a plurality of flexible off-takes connected to the suction manifold and extending radially in-

wardly toward the film-negative, said off-takes each terminating in a suction cup adapted to be disposed upon the outer surface of the film-negative when the latter is operatively mounted upon the cylinder, and relatively thin tape-like elements adapted to be placed upon the photo-sensitized surface of the cylinder to frame the area in which the exposure is to be made and underlie the margins of the film-negative thereby sealing the space between the photo-sensitized surface and the film-negative in the area of the exposure to permit substantially complete evacuation of said space.
